UNITED STATES PATENT OFFICE

134,528

DESIGN FOR A DISPLAY STANDARD

Nace F. Huber, Louisville, Ky.

Application July 20, 1942, Serial No. 107,629

Term of patent 3½ years

To all whom it may concern:

Be it known that I, Nace F. Huber, a citizen of the United States of America, residing at Louisville, in the county of Jefferson and State of Kentucky, have invented a new, original, and ornamental Design for a Display Standard, of which the following is a specification, reference being had to the accompanying drawing, forming part thereof.

Fig. 1 is a perspective view of a display standard, taken from the reverse side, and

Fig. 2 is a top plan view of the display standard illustrated in Fig. 1.

The characteristic features of my design reside in the portions shown in full lines.

I claim:

The ornamental design for a display standard, as shown and described.

NACE F. HUBER.
